[57] **CLAIM**

The ornamental design for the rotatable mountable multiple electrical outlet power stake, as shown and described.

DESCRIPTION

FIG. 1 is a top perspective view of a rotatable multiple electrical outlet power stake;

FIG. 2 is a left side view, and is a right side view, of the power stake of FIG. 1;

FIG. 3 is a top view of the power stake of FIG. 1;

FIG. 4 is a front view of the power stake of FIG. 1;

FIG. 5 is a rear view of the power stake of FIG. 1; and,

FIG. 6 is a bottom view of the power stake of FIG. 1.
